UNITED STATES PATENT OFFICE.

JÖRGEN BJÖRNSTAD, OF READING, ENGLAND.

APPARATUS FOR PRODUCING SOUND.

1,339,158.

Specification of Letters Patent.

Patented May 4, 1920.

Application filed September 8, 1919. Serial No. 322,541.

To all whom it may concern:

Be it known that I, JÖRGEN BJÖRNSTAD, a subject of the King of Great Britain and Ireland, residing at Reading, in the county 5 of Berks, England, have invented Improvements in Apparatus for Producing Sound, of which the following is a specification.

This invention relates to sound producing apparatus of the kind described in the 10 specification of British Letters Patent No. 25268 of 1905, and known as a siren or dia- phone, suitable for fog signaling and like purposes, in which the sound is produced by the action of fluid under pressure flowing 15 through a slotted rotary piston that is reciproated within a stationary slotted cylinder by the action of a fluid medium, and more particularly to apparatus of the kind referred to wherein the fluid medium used 20 is steam.

In apparatus of this kind, the piston usually consists of two integrally connected portions, the larger of which, constituting the driving portion, is about double the area of 25 the smaller or sound producing portion. In such apparatus it is essential to satisfactory working that an efficient cushion should be formed between the driving portion of the piston and the cylinder by the compression 30 of the driving medium at the end of the outward stroke of the piston, so as to prevent metallic contact between the driving portion of the piston and the cylinder which would otherwise result in mechanical damage and 35 ultimate breakdown.

The efficiency of this compression obviously depends on the one hand, on the provision of a sufficiently close fit between the sound-producing portion of the piston and 40 the corresponding portion of the cylinder to prevent the leakage, between them, of the pressure medium and the consequent reduction in the efficiency of the cushion. In order to insure prompt starting of the apparatus 45 immediately upon admission of working fluid, it is, on the other hand, necessary that the piston should be quite free at the moment of starting.

It is easy to satisfy these somewhat conflicting conditions when working with compressed air, because the expanding air has the effect of cooling the sounding portion of the piston, which is very thin and light in comparison with the cylinder, so that the 55 piston contracts in diameter to a slight ex-

tent and thereby increases the clearance between it and the cylinder at the moment of starting and before the cylinder has had time to be cooled to the same temperature, and when the piston has once got a good 60 start, the subsequent reduction in clearance does not matter, because there is then ample driving power.

When however steam is used as the driving medium, the hot steam expands the 65 sound-producing portion of the piston before the cylinder can expand to an equal extent, with the result that the clearance between the two is reduced and the piston is therefore liable to stick and fail to start 70 until the cylinder has had time to get heated to the same temperature, so as to restore the original clearance.

An attempt to obviate the difficulty merely by increasing the clearance between the piston and cylinder would result in impairing the efficiency of the compression cushion and bringing about metallic contact between the piston and cylinder with its resultant 75 damage. Such increase of clearance is, however unavoidable, where prompt starting of the piston is necessary.

According to the present invention sufficient clearance is provided between the piston and cylinder to permit of prompt starting 80 and in order to maintain or restore the compression of the cushion, there is introduced between the sounding portion of the piston and the cylinder, a steam packing 85 whereby leakage of steam from the compression or cushioning space is minimized or avoided.

To this end, according to one construction, the slits in the sounding portion of the piston are arranged at a greater distance from 90 the driving portion of the piston than heretofore, so as to leave room for the formation in the cylinder of one or more extra slits or holes which are formed in the cylinder opposite to a plain part of the sounding portion of the piston, the arrangement being 95 such as to keep the clearance space between the sounding portion of the piston and the cylinder filled with a film of high pressure steam. Further to reduce the risk of leakage of steam, shallow grooves are or may be provided in the surface of the cylinder, or of the sounding portion of the piston, or in both surfaces, in proximity to the slit or slits, say, on each side of it or them. 100 105 110

One such constructional example of dia-
phone embodying the invention is illus-
trated in central vertical section in the ac-
companying drawing, the piston to the
right of the center line being shown in the
starting position and to the left of such line
at the opposite end of its stroke. In this
instance the cylinder *a*, of the ordinary
differential shape, is provided in its smaller
portion with a circumferential slit *b*, sup-
plied with steam from the annular chamber
c, in the same way as are the sounding slits
d in such smaller portion of the cylinder.
A shallow circumferential groove *e* and two
similar grooves *e'* are formed in the inner
surface of the cylinder *a* and arranged in
relation to the slit *b*, as shown, so as to re-
ceive steam therefrom and form a steam
packing. Or, similar shallow grooves may
be formed in the outer surface of the dif-
ferential piston *h*, or in both of said sur-
faces, as shown, for the purpose mentioned.

With this arrangement, when steam is
compressed in the compression or cushion-
ing space *f* above the larger and driving
portion *g* of the differential piston, it will,
under the circumstances described, then
have opposed to it a back pressure in the
clearance space between the smaller sound-
ing portion *h* of the piston and the smaller
portion of the cylinder *a*, equal, or nearly
so, to its own pressure instead of that of the
external atmosphere. As a result of this,
there is a very considerable reduction in the
leakage of steam from the said compression
or cushioning space *f* and consequent in-
crease in the resultant pressure of compres-
sion and the elimination of metallic contact.

What I claim is:—

40 1. Apparatus of the kind referred to,
comprising a differential piston, a corre-
sponding cylinder between which and the
piston a cushioning space is provided and
means whereby leakage of fluid from such
space is prevented or reduced, for the pur-
pose set forth.

2. Apparatus of the kind referred to,
comprising a differential piston the larger
portion of which serves as a driving mem-
ber and the smaller portion as a sounding
member, a differential cylinder for such
piston, means whereby a portion of the
driving fluid is imprisoned between the cyl-
inder and piston to cushion the movement
55 of the latter as it approaches the end of its
stroke and means whereby another portion
of the fluid is caused to serve as a packing
for preventing or minimizing leakage of the
cushioning fluid between the wall of the

smaller cylinder portion and the companion 60
sounding member of the piston.

3. In apparatus of the kind referred to, a
differential cylinder the smaller portion of
which is formed with a series of sounding
slits extending to an annular surrounding 65
steam space and with a circumferential slit
between the sounding slits and the larger
portion of the cylinder, one at least of the
adjacent surfaces of the smaller portions of
the piston and cylinder being formed with 70
circumferential grooves adapted to receive
steam from the said circumferential slit, for
the purpose specified.

4. In apparatus of the kind referred to, a
differential cylinder the smaller portion of 75
which is formed with a series of sounding
slits extending to an annular surrounding
steam space, with a circumferential slit be-
tween the sounding slits and the larger por-
tion of the cylinder and with a circum- 80
ferentially grooved inner surface adapted to
receive steam from the said circumferential
slit, for the purpose specified.

5. In apparatus of the kind referred to,
a differential cylinder the smaller portion 85
of which is formed with a series of sounding
slits extending to an annular surrounding
steam space, with a circumferential slit be-
tween the sounding slits and the larger por-
tion of the cylinder and with shallow cir- 90
cumferential grooves disposed upon the in-
ner surface at opposite sides of the circum-
ferential slit aforesaid, for the purpose
specified.

6. Apparatus of the kind referred to, 95
comprising a differential cylinder the smaller
portion of which is formed with a series
of sounding slits surrounded by an annular
steam chamber, a differential piston having
a sounding portion occupying the smaller 100
cylinder portion and a driving portion
adapted to work in the larger cylinder por-
tion, means whereby a portion of the steam
is periodically imprisoned between the driv-
ing portion of the piston and the opposed 105
surface joining the large and small cyl-
inder portions and means constituting a steam
packing adapted to prevent or reduce leak-
age of the imprisoned steam, such means
comprising a circumferential slit in the 110
smaller cylinder portion and shallow cir-
cumferential grooves in the inner surface of
the latter disposed at opposite sides of the
slit.

Signed at London this 14th day of August 115
1919.

JÖRGEN BJÖRNSTAD.
